INSPECTION LIGHT FOR JET PLANE FUEL
CELLS AND THE LIKE

William W. Wittie, Chicago, Ill., assignor to
Blowers, Inc., Blue Island, Ill.

Application May 16, 1958, Serial No. 50,931

Term of patent 14 years

(Cl. D48—20)

Fig.1.

Fig.2.

Fig.3

Fig. 1 is a top plan view of an inspection light for jet plane fuel cells, showing my new design;

Fig. 2 is a side elevational view thereof; and

Fig. 3 is an enlarged fragmentary perspective view of the light as seen from the right of Fig. 2 with portions thereof shown in alternate position.

I claim:

The ornamental design for an inspection light for jet plane fuel cells and the like, as shown.
